UNITED STATES PATENT OFFICE.

CHARLES J. HODGE, OF HOOGLTON, MICHIGAN.

DESIGN FOR A FRAME FOR SUPPORTING ORE OR MINERAL WASHING JIG-SCREENS.

SPECIFICATION forming part of Design No. 29,933, dated January 3, 1899.

Application filed December 12, 1898. Serial No. 699,073. Term of patent 7 years.

To all whom it may concern:

Be it known that I, CHARLES J. HODGE, a citizen of the United States, residing at Houghton, in the county of Houghton and State of Michigan, have invented and produced a certain new and original Design or Useful Shape for a Frame for Supporting Ore or Mineral Washing Jig-Screens, of which the following, in connection with the accompanying drawings, is a full, clear, and exact specification.

In the said drawings, Figure 1 is a plan view of a frame of the character described embodying my design; and Fig. 2 is a side elevation thereof, partly in section, on the irregular line 2 2.

The leading features of my design consist of the marginal frame portion A and the comparatively narrow deep cross-bars B C, extending diagonally across the frame A and forming diamond-shaped openings, with their faces or upper surfaces substantially flush with the face or upper surface of the frame A.

The frame A is rectangular and oblong, and at short intervals throughout its upper surface it is provided with sockets or cavities a, each surrounded on the inner side by a boss a', and between these bosses the inner upper

edges of the frame A are beveled or rounded, as shown at a'.

The cross-bars B C are intermerged with each other and also with the frame A, and they are very deep as compared with their width and coterminous in depth with the frame A, both their upper and lower surfaces being flush with or in the same plane as the upper and lower surfaces of the frame A, and such cross-bars are also tapered from their extreme lower edges to their upper edges, which latter are rounded, as shown in Fig. 2.

At a short distance from one end of the frame and at substantially the mid-length of such end is formed a circular perforated boss D, which occurs at the intersection of two of the cross-bars B C, into which the cross-bars merge.

Having thus described my invention, what I claim as new therein, and desire to secure by Letters Patent, is—

The design for a frame for supporting ore or mineral washing jig-screens substantially as herein shown and described.

CHAS. J. HODGE.
